SPACING APPARATUS

Harry J. Criner, Davenport, Iowa, assignor of one-half to A. G. Bush, Davenport, Iowa

Application September 3, 1938, Serial No. 228,431

20 Claims. (Cl. 146—153)

My invention relates to improvements in spacing apparatus and the objects of my invention are to provide an improved means for adjustably spacing the blades of bread slicing or other machines which may be applied to either reciprocating machines or band blade machines and may also be utilized as a mechanical movement wherever adjustable variable spacing of parts is required. Also, to provide apparatus by which parts may be adjustably spaced at either a fixed maximum or minimum distance apart as well as at any intermediate point between such minimum and maximum. Other objects will appear from my description.

15 I attain these objects by the means illustrated in the accompanying drawings, in which

Figure 1 is an horizontal section on the line 1—1 of Figure 2;

Figure 2 is a vertical section on the line 2—2 of Figure 1;

Figure 3 is an enlarged sectional detail showing the upper tubular member and connected parts on the line 3—3 of Figure 2;

Figure 4 is an enlarged sectional detail of a portion of the upper tubular member and included parts;

Figure 5 is an enlarged detail of an alternate form of linkage showing a portion of the upper member in section;

Figure 6 is an enlarged detail showing an alternate form of means for adjusting relative spacing of the carrier pins;

Figure 7 is an end elevation of Figure 6;

Figure 8 is an enlarged detail end view of one of the carrier pins with the adjusting spring and blade in place; and

Figure 9 is an enlarged detail showing a portion of the adjusting bar.

My apparatus comprises upper and lower tubular members 1 and 2 spaced apart and held rigidly in fixed relation by sidebars 3 mounted upon a suitable frame F, lugs B or other suitable means of support.

In the case of reciprocating machines, the sidebars 3 may be mounted for reciprocating vertical travel in the lugs B, and in the case of band-blade machines, they may be adjustably mounted in the lugs B and secured in place by set screws or any other desired means.

The upper and lower members 1 and 2 are preferably formed of rectangular tubes as shown in Figure 3, each having a front slot 18 open at one end of the tube and extending to within a short distance from the opposite end.

55 A chain of the sprocket chain type is mounted in the upper member. Each link of this chain comprises a pair of flat link-bars spaced apart and having their ends united by pivots 7 and 9. The inner links are numbered 4 and the outer links are numbered 5 as shown in Figure 1. The

links 4 are arranged in inner parallel pairs and the links 5 are arranged in outer parallel pairs.

Rollers 6 and 8 may be mounted between the links upon the pivots 7 and 9 to properly space the links 4 from each other and hold them in 5 parallel position.

The links 5 are spaced apart by the links 4 and held in parallel position by the links 4 and the adjacent sidewalls of the upper tubular member 1.

The innermost pivot of the chain is rigidly secured in place by an extension through an opening in the rear wall of the tubular member 1.

For convenience, I have referred to the lower 15 wall of the tubular member 1 as being the floor and to the upper wall as shown in said Figure 1 as the ceiling; also to the left wall as shown in Figure 3 as the rear, and to the right wall as the front of said member.

The pivots 7 are all formed of a length to fit closely but to slide freely within the sidewalls of the member 1. The pivot-shafts or carrier pins are also slideably mounted in the tubular member 1 but are formed with extensions 10 25 which project outwardly through the slot 18 in the front wall. The extensions 10 are also slotted as at 12 to receive the slicing blades 13 and to guide or carry them as the case may be.

The pivot 9 of the outermost link of the chain extends rearwardly from the upper member 1 through a slot 17 formed in the rear wall of the member 1 and is provided with a handle 16 to assist in its manual operation. The slot 17 is not shown in the upper member but is in all respects similar to the slot 17 formed in the lower member 2 as shown in Figure 2.

The chain is so mounted within the member 1 that the side-links 4 and 5 all stand at an angle of approximately forty-five degrees to the bottom or floor and the pivots 9 or the rollers 8 mounted thereon all rest on the floor of the member. The pivots 7 or the rollers 6 mounted thereon when in their closest adjustment bear against the ceiling or top of the member 1 and at their widest spacing the pivot 7 or rollers 6 stand a short distance below the ceiling of the member 1 as shown in Figure 4.

The pivots 1 may be formed with the central portions thereof having substantially the diameter shown by the rollers 6 as desired, but I prefer to use the rollers 6 and 8 to facilitate the movement of the chain lengthwise of the member 1, thus the floor and ceiling of the channelled member 1 may fix the limit of spacing movement of 55 the pivot extensions 10 and blades 13.

In Figures 2, 3 and 4 I have shown additional flat links 11 and 11' mounted upon the pivots 9 or roller-sleeves 8 between the links 4 and 5 to limit their relative movement in either direction and 60

these links have elliptical openings 12' which allow the desired movement of the pivots 9 either towards or away from each other and limit such movements within fixed limits. When these 5 additional links are used the sleeve rollers 6 need not contact the ceiling as a stop.

For ordinary purposes, a play of one-sixteenth of an inch for each of these sleeve-rollers 8 or pivots 9 within its adjacent elliptical openings 10 10 12' will be sufficient as the most popular thickness for slices of bread is one-half inch for white bread and three-eighths of an inch for dark breads, but it is obvious that greater or less play may be provided as desired.

15 In order to provide the necessary tension upon the slicing blades, I provide a flat spring 15 with slotted ends, one end of which is adapted to seat in a notch 14 formed in the pivot-shaft 10 and the other end of which is formed with a hook 20 15' adapting it to embrace a pin 13' rigidly secured in one end of the blade 13. The ends of the springs 15 are slotted so as to straddle the blades 13 as shown in Figures 7 and 8.

25 The lower tubular member 2 corresponds in every way to the upper member 1 and carries a similar chain in a similar way but in reversed position, the pivots 9' being mounted adjacent the ceiling of the channel member and the pivots 7' being adjacent the lower part or floor of the member 2.

30 In Figure 5 I have shown an alternate form of stop or detent to limit the spread of the pivots 9, which comprises an arm 4' formed integral with side-link 4 and adapted to bear against the floor of the member 1 so as to prevent the pivot 7 from descending any nearer to the floor and thus prevent any further spreading or lengthening of the chain.

35 In Figures 6, 7 and 9, I have shown alternate means for controlling and varying the spacing of the pivot extensions 10. This consists of forming the tubular member 1 integral with an extension 1' in which a shaft or tube 18a is revolvably mounted, the outer end of which carries a 40 transverse slot 18b by which same can be rotated by a screw driver or other suitable tool.

45 A longitudinal slot 19 is cut in one side of the shaft 18a. The upper row of chain pivots 6'' are formed with extensions carrying rounded heads 6' formed integral with the pivots 6''. These heads 6' extend into the groove 19. A set screw 26 is secured in the housing 1', the inner end of which contacts the shaft 18a to lock it in any given position.

50 With this form, when desired to widen the spacing of the blades 13 the set screw 26 is loosened and the shaft 18 turned in such a way as to force the pivots 6'' downwardly the desired distance and as the lower end of the links 4 and 5 or the 55 rollers 8 are limited in their downward movement by the floor of the channel member 1, the downward movement of the pivots 6'' necessarily slides the pivots 8' apart carrying with them the extensions 10 and the blades 13. When moved the desired distance, the set screw 26 is locked in place and the apparatus is ready for operation.

60 In this alternate form, the lower channel member is made to correspond with the upper one in all respects and in assembling them the shafts 70 18a are placed in the same relative position in the upper and lower members so that the direction of the screw-driver slot 18b can be used as a gauge to indicate corresponding positioning of the upper pivots 7.

65 75 When applied to reciprocating machines, two

sets of upper and lower tubular members 1 and 2 with their side-bars 3 are utilized and are faced in opposite directions so that the extensions 10 of one set will alternate with the extensions 10 of the other set and the blades will reciprocate 5 vertically with their cutting edges substantially in a vertical plane.

When applied to band blade machines, two sets of channel members may be used with the extensions 10 of one set alternating with the 10 extensions of the other set and they may be mounted upon the frame of the machine in such spaced relation as the requirements of each particular case may demand.

It is obvious that various modifications of my 15 apparatus may be made without departing from the spirit of my invention and I do not limit my claims to the precise forms shown in the drawings.

I claim:

1. In a bread slicing machine, a blade guiding assembly comprising parallel hollow rectangular upper and lower cross-members united at their ends by parallel side-bars, parallel longitudinal slots formed in the front and rear of the cross-members the front slots extending from one end thereof nearly to the opposite end, and the rear slots extending lengthwise of said members from one end a distance substantially equal to the sum of the desired travel of all the pivot-shafts in either series, separate series of pivot-shafts 20 mounted in said cross-members, respectively, each pivot-shaft having an extension passing outwardly through its corresponding front slot and being slotted to receive a slicing blade, the inner ends of said pivot-shafts forming alternate pivots 25 of chains and being connected by flat links to alternating pivots slidably mounted within said cross-members respectively, the innermost pivot-shaft of each series being rigidly units to its respective cross-member and the outermost pivot-shafts of both series having their rear ends extended so as to pass through the rear slots, and handles united to the rear extensions of the outermost pivot-shafts of each series by which their 30 position can be manually adjusted.

40 45

2. In a bread slicing machine, a blade guiding assembly comprising parallel hollow rectangular upper and lower cross-members united at their ends by parallel side-bars, parallel longitudinal front slots formed in the cross-members extending from one end thereof nearly to the opposite end, rear slots formed in the opposite sides of the cross-members, separate series of pivot-shafts mounted in said cross-members respectively, each pivot-shaft having a slotted extension passing outwardly through its corresponding front slot to receive a slicing blade, the inner ends of said pivot-shafts forming the alternate pivots in chains being connected by flat links to additional pivots slidably mounted within said cross-members respectively in alternation with the pivot-shafts said pivot-shafts in each chain lying in a single horizontal plane and the alternating pivots lying in a similar plane spaced above or below the plane of the pivot-shafts, the innermost pivot-shaft of each series being rigidly united to its respective cross-member and the outermost pivot-shafts of both series having their rear ends extended so as to pass through the rear slots which extend lengthwise of said members a distance substantially equal to the sum of the travel of all the pivot-shafts in either series, and handles united to the rear extensions of the outermost pivot-shafts by which they can be manually actuated.

55

60 65 70 75 80 85 90 95

3. In a bread slicing machine, a blade guiding assembly comprising rectangular tubular upper and lower cross-members united at their ends by parallel sidebars, parallel longitudinal slots formed in the fronts of the cross-members extending from one end thereof nearly to the opposite end, a separate series of pivot-shafts mounted in each of said cross-members having extensions passing outwardly through the front slots, said extensions being slotted to receive the ends of the slicing blades, the inner ends of said pivot-shafts forming the alternate pivots of chains of the sprocket type, and being connected by flat links to additional pivots slidably mounted within said cross-members respectively in alternation with the pivot-shafts and lying in a horizontal plane spaced from the pivot-shafts, the innermost pivot-shaft or carrier pin of each series being rigidly united to its respective cross-member and the outermost pivot-shafts of both series having their rear ends extended so as to pass through additional slots formed in the rear of said cross-members parallel to the first mentioned longitudinal slots and extending lengthwise of said members a distance substantially equal to the sum of the travel of all the pivot-shafts in either series, and handles united to the rear extensions of the outermost pivot-shafts by which they can be manually actuated lengthwise of the tubular members.
4. In a bread slicing machine, a blade guiding assembly comprising rectangular tubular upper and lower cross-members united at their ends by parallel sidebars, parallel longitudinal slots formed in the fronts of the cross-members extending from one end thereof nearly to the opposite end, a separate series of pivot-shafts mounted in each of said cross-members, having extensions passing outwardly through the front slots, said extensions being slotted to receive the ends of the slicing blades, the inner ends of said pivot-shafts forming the alternate pivots of chains of the sprocket type, and being connected by flat links to additional pivots slidably mounted within said cross-members respectively in alternation with the pivot-shafts and lying in a horizontal plane spaced from the pivot-shafts, the innermost pivot-shaft or carrier pin of each series being rigidly united to its respective cross-member in combination with tubular housings united to said cross-members, grooved shafts rotatably mounted therein, rounded heads united to the additional pivots and extending into the grooves of the shafts to be actuated thereby whereby the planes of said additional pivots may be raised or lowered, and set screws threaded in the housings to lock the rotatable shafts in adjusted position therein.
5. In a bread slicing machine, the combination with a supporting frame having a plurality of slicing blades mounted for longitudinal travel thereon, of blade guiding assemblies comprising parallel hollow rectangular upper and lower cross-members united at their ends by parallel sidebars and having parallel front and rear slots formed therein, separate series of pivot-shafts mounted in said cross-members respectively, each pivot-shaft having a slotted extension passing outwardly through the front slot to guide a slicing blade, the inner ends of said pivot-shafts forming the alternate pivots of chains and being connected by flat links to additional alternating pivots slidably mounted within said cross-members respectively, the innermost pivot-shaft of each series being rigidly united to its respective cross-member and means united to the outermost pivot-shafts of both series to move same along the cross-members a distance equal to the sum of the travel of all the pivot-shafts in either series.
6. In a bread slicing machine, a blade guiding assembly comprising rectangular tubular upper and lower cross-members united at their ends by parallel sidebars, parallel longitudinal slots formed in the fronts of the cross-members extending from one end thereof nearly to the opposite end, a separate series of pivot-shafts mounted in each of said cross-members, having extensions passing outwardly through the front slots, said extensions being slotted to receive the ends of the slicing blades, the inner ends of said pivot-shafts forming the alternate pivots of chains of the sprocket type, and being connected by flat links to additional pivots slidably mounted within said cross-members respectively in alternation with the pivot-shafts and lying in a horizontal plane spaced from the pivot-shafts, the innermost pivot-shaft or carrier pin of each series being rigidly united to its respective cross-member in combination with tubular housings united to said cross-members, grooved shafts rotatably mounted therein, rounded heads united to the additional pivots and extending into the grooves of the shafts to be actuated thereby whereby the planes of said additional pivots may be raised or lowered, and set screws threaded in the housings to lock the rotatable shafts in adjusted position therein.
7. In a bread slicing machine, the combination with a supporting frame having a plurality of slicing blades mounted for longitudinal travel thereon, of blade carrying assemblies comprising parallel hollow rectangular upper and lower cross-members united at their ends by parallel side-bars and having parallel front and rear slots formed therein, separate series of pivot-shafts mounted in said cross-members respectively, each pivot-shaft having a slotted extension passing longitudinally of the links.
8. In a structure as described in claim 7, additional links connecting the successive pivot-shafts to each other but having extended openings therein to embrace the pivot-shafts which permit a limited movement of the pivot-shafts longitudinally of the links.
9. In a bread slicing machine, the combination with a supporting frame having a plurality of slicing blades mounted for longitudinal travel thereon, of blade carrying assemblies comprising parallel hollow rectangular upper and lower cross-members united at their ends by parallel side-bars and having parallel front and rear slots formed therein, separate series of pivot-shafts mounted in said cross-members respectively, each pivot-shaft having a slotted extension passing

- outwardly through the front slot to guide a slicing blade, the inner ends of said pivot-shafts forming the alternate pivots of the chains and being connected by flat links to additional alternating pivots slidably mounted within said cross-members respectively, the innermost pivot-shaft of each series being rigidly united to its respective cross-member and means united to the outermost pivot-shafts of both series to move same along the cross-members a distance equal to the sum of the travel of all the pivot-shafts in either series.
10. In a bread slicing machine, the combination with a supporting frame having a plurality of slicing blades mounted for longitudinal travel thereon, of blade carrying and spacing assemblies comprising parallel hollow rectangular upper and lower cross-members united at their ends by parallel sidebars and having parallel front and rear slots formed therein, separate series of pivot-shafts mounted in said cross-members respectively, each pivot-shaft having a slotted extension passing outwardly through the front slot to guide a slicing blade, the inner ends of said pivot-shafts forming the alternate pivots of the chains and being connected by flat links to additional alternating pivots slidably mounted within said cross-members respectively, the innermost pivot-shaft of each series being rigidly united to its respective cross-member means united to the outermost pivot-shafts of both series to move same along the cross-members a distance equal to the sum of the travel of all the pivot-shafts in either series and resilient means to unite the ends of the blades to their respective carrying pivot-shafts.
11. A structure as described in claim 1, in combination with means to limit the gathering and the spreading movement of the pivot-shafts.
12. In a bread slicing machine, the combination with a supporting frame having parallel slicing blades mounted for longitudinal travel therein, of adjustable blade-spacing mechanism comprising a pair of chains of the sprocket type having alternate pivots extended beyond the links and slotted to receive the blades respectively, the alternate links of said chains having elongated pivot openings to permit variable spacing of the pivots therein, supporting means to carry said chains at parallel fixed levels, and means for spreading apart or gathering nearer together the blade-engaging pivots at fixed limits of travel.
13. A mechanical movement for longitudinally spacing a series of guiding or carrying members, comprising a tubular bar, a chain of the sprocket type slidably mounted therein the alternate pivots of said chain having united thereto the guiding or carrying members in series, the alternate links of said chains having elongated pivot openings to permit variable spacing of the pivots therein, supports to carry said alternate pivots in a given plane, the intermediate pivots being arranged in a parallel plane spaced therefrom, and means as described to cause the planes of the intermediate pivots to approach toward or separate from the planes of the carrier pivots.
14. In a bread slicing machine, a support, a rectangular frame mounted for reciprocation in said support having tubular upper and lower crossbars, each of said bars carrying spacing apparatus as set out in claim 13.
15. In a spacing mechanism, a support, a multiple link sprocket type chain slidably mounted thereon with alternate pivots adjacent the support and intermediate pivots adjustably secured in a common plane parallel to and spaced from the support, the alternate pivots being provided with extensions to carry or guide a plurality of the members to be spaced and stops to limit the adjusting movement in either direction the alternate links of said chains having elongated pivot openings to permit variable spacing of the pivots therein.
16. In a spacing mechanism, the combination with a frame, of a pair of chains of the sprocket type mounted thereon in spaced relation having alternate pivots extended and slotted to receive and guide slicing blades, the alternate links of said chains being formed with longitudinally extended pivot seats or openings whereby the spacing of the pivots therein may be varied within fixed limits toward or from each other.
17. A bread slicing machine as described in claim 7, the slotted extensions of the pivot shafts being arranged in opposed pairs and each pair carrying a slicing blade, transverse pins united to the blades near opposite ends thereof, notches in the outer edges of the slotted extensions, U-shaped springs with their ends slotted to straddle the blades, each having one end indented to engage the adjacent pin in the blade and its opposite end flanged or turned to enter the notch in its corresponding slotted extension.
18. A combination in a bread slicing machine as described in claim 7, said slotted fingers being arranged in spaced pairs, the fingers of each pair being notched on opposite sides, slicing blades having transverse pins rigidly united thereto approximately at each end thereof, U-shaped springs each having its ends slotted to straddle the blades and carrying an indentation at one end to engage one of said transverse pins on each side of a given blade and having its opposite end flanged or turned to enter the adjacent notch in its corresponding finger.
19. In a bread slicing machine, the combination with a support, of blade carrying means mounted thereon for longitudinal reciprocating travel, including a plurality of spaced, slotted fingers arranged in spaced pairs and notched on opposite sides, transverse pins united to the blades near opposite ends thereof, a plurality of U-shaped springs arranged to straddle the blades, each having one end indented to engage one of said pins and its opposite end flanged or turned to enter the notch in the corresponding slotted finger to exert pressure upon the pin and upon the finger in opposite directions.
20. In a bread slicing machine having a support, blade carrying means mounted thereon for longitudinal reciprocating travel including a plurality of spaced, slotted fingers arranged in spaced pairs and notched on opposite sides, tensioning means for the blades comprising transverse pins united to the blades near opposite ends thereof, and a plurality of slotted springs arranged to straddle the blades each having one end indented to engage one of said pins and its opposite end flanged or turned to enter the notch in the corresponding slotted finger to exert pressure upon the pin and upon the finger in opposite directions.
